UNITED STATES PATENT OFFICE.

WILLIAM H. SAART, OF ATTLEBOROUGH, MASSACHUSETTS, ASSIGNOR TO
THE JAMES E. BLAKE COMPANY, OF SAME PLACE.

DESIGN FOR A HANDLE FOR BUTTON-HOOKS, &c.

SPECIFICATION forming part of Design No. 31,067, dated June 27, 1899.

Application filed June 2, 1899. Serial No. 719,149. Term of patent 3½ years.

To all whom it may concern:

Be it known that I, WILLIAM H. SAART, of Attleborough, in the county of Bristol and State of Massachusetts, have invented and 5 produced a new and original Design for the Handle of a Button-Hook or Similar Article, of which the following is a specification, reference being had to the accompanying drawings, forming part thereof.

10 Figure 1 is a side view of a handle, showing my design secured to a button-hook, the blade of a paper-cutter being indicated in broken lines. Fig. 2 is a transverse sectional view of the handle on the line A A in Fig. 1.

15 The leading feature of my design consists in the scalloped margin of the handle ornamented with raised leaves extending from two segmental lines inclosing a central panel, as will be more fully set forth hereinafter.

20 In the drawings, B indicates the blade, and C the stem, of the handle, and D the button-hook. At the junction of the handle with the article to which it is attached the bulbous enlargement a is ornamented by a series of convex bulbs,

25 terminating in the surface of the lower end of the stem below the inwardly-curved contracted portion b, from which extend upward the stems of the foliated scrolls c c, curving

outward and then inward to the pendent ornament e, which extends downward over the 30 widest portion of the stem between two strings of graduated semispherical beads. From the center, above the foliated scrolls c c, extends the foliated scroll d. On each side of the convex panel f, which is inclosed by two segmental raised lines uniting in points at the 35 opposite ends, the scrolled leaves g g extend diagonally over the scallops h h on each side of the blade of the handle, and three bulbous leaves spring from the rose ornament at the 40 upper end of the convex panel f over the scallop i, forming the end of the blade of the handle, presenting to the eye the appearance of a long-pointed panel inclosed in a fan-shaped border. 45

Having thus described my invention, what I claim as new, and desire to secure by Letters Patent, is—

The design for the handle of a button-hook or similar article herein shown and described. 50

In witness whereof I have hereunto set my hand.

WILLIAM H. SAART.
